DESIGN FOR A RIBBON

Solomon Graff, New York, N. Y., assignor to Eagle
Pleating & Stitching Co. Inc., New York, N. Y., a corporation of New York

Application October 15, 1938, Serial No. 80,475

Term of patent 3½ years

To all whom it may concern:

Be it known that I, Solomon Graff, a citizen of the United States, residing at New York, in the county of Bronx and State of New York, have invented a new, original, and ornamental Design for Ribbon, of which the following is a specification, reference being had to the accompanying drawing, forming a part thereof, wherein:

Fig. 1 is a face view of a ribbon showing my design and in partially extended position;

Fig. 2 is a side elevation of the ribbon shown in Fig. 1;

Fig. 3 is a bottom plan view of the ribbon shown in Fig. 1, and

Fig. 4 is an end view of the ribbon shown in Fig. 1.

I claim:

The ornamental design for ribbon, as shown.

SOLOMON GRAFF.
